UNITED STATES PATENT OFFICE.

MARION N. TOMBLIN, OF AURORA, ILLINOIS.

COIN-ACTUATED MECHANISM.

SPECIFICATION forming part of Letters Patent No. 769,781, dated September 13, 1904.

Application filed May 1, 1902. Serial No. 105,470 (No model.)

To all whom it may concern:

Be it known that I, MARION N. TOMBLIN, a citizen of the United States, residing at Aurora, in the county of Kane and State of Illinois, have invented certain new and useful Improvements in Coin-Actuated Mechanism, of which the following is a full, clear, and exact specification.

My invention relates to coin-actuated mechanism for general purposes, and the improvements have especial reference to means for detecting bogus, imperfect, and improper coins.

The primary object of my invention is to provide improved and simple means for preventing the insertion of a perforated coin or slug or bogus coins or slugs composed of soft material.

With these ends in view my invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is a vertical sectional view of my improved apparatus. Fig. 2 is an enlarged detail vertical sectional view taken on the line 2 2, Fig. 1. Fig. 3 is a detail plan section taken on the line 3 3, Fig. 2. Fig. 4 is a similar section on the line 4 4, Fig. 2.

1 is any suitable box or casing at the top or any other appropriate place, in which is formed a coin-admission slot 2, under which within the casing 1 are placed two plates or flanges 3 4, which constitute the edges of the upper end of the coin-chute.

Arranged directly under the coin - slot 2 within the vertical part of the upper end of the coin-chute and on the same side thereof is a plurality of juxtaposed vertical fingers 7, which are pivoted at their lower ends by a pin or pintle 8 or any other suitable means to the lower end of a swinging gate or block 9, whose upper end is supported by pivots 10 or any other suitable means in the side edges 3 4 of the coin-chute. The upper ends of the fingers 7 are provided with points 11, which are turned toward the coin-slot 2, and when

the parts are in their normal position, as shown in Fig. 2, all of these points 11 stand contiguous to the edge of the coin-slot 2, and the pivoted gate 9, whose pivot is located a considerable distance below the points 11, is provided on its inner face adjacent to the slot 2 with a cam or incline 12, which when the parts are in their normal position, as shown in Fig. 2, stands across or projects materially into the coin-chute, so as to intercept the coin, the upper end of the gate 9 being permanently located out of the line of movement of the coin, so that any coin which will pass through the slot 2 will also pass the pivotal end of the gate 9, but will not pass the cam or incline 12 without deflecting it outwardly or away from the coin-chute, and in thus deflecting the gate 9 it will be seen that the lower ends of the finger 7 will be thrown outwardly and their upper ends consequently thrown inwardly on an arc around the pivot 10, and should the coin which is then being inserted have any material mutilation or possess a perforation one or more of the points 11, which are arranged close together, will find such mutilation or perforation and by digging inwardly against the coin arrest its further descent with a resistance directly equal to the power with which it is pressed into the coin-slot. Should the coin, however, be a proper one in normal condition, it will merely slide below the points 11, which can gain no material purchase against it, and after passing the incline 12 will drop by gravity into the coin-chute, and after the coin shall have thus passed the incline 12 the pivoted gate 9 and its connected parts will swing back to their normal position, as shown in Fig. 2, by gravity. Ordinarily the points 11 will engage the coin with sufficient pressure by their mere gravitation against it; but in order to better insure close contact with the coin I prefer to provide each of the fingers 7 with a spring 13, which bears against the back of the finger and is secured at its lower end in a suitable support of cross-bar 14, carried by the lower end of the gate 9 at a sufficient distance from the lower ends of the fingers 7 to permit of their oscillation independently of the gate.

15 is a cross-bar which constitutes a stop for

limiting the backward or outward movement of the fingers 7 and preventing the same from tilting too far away from the path of the coin.

Having thus described my invention, what I claim as new therein, and desire to secure by Letters Patent, is—

1. In an apparatus for the purpose described the combination of a casing having a coin passage or path, a depending swinging gate projecting into said path, a finger pivotally supported at the lower free end of said gate and having its other end arranged contiguous to the path of the coin and adapted to impinge the latter, substantially as set forth.
2. In an apparatus for the purpose described the combination of a casing having a coin passage or path, a depending swinging gate projecting into said path, a finger pivotally supported at the lower free end of said gate and having one end projecting above the gate and arranged contiguous to the path of the coin and adapted to impinge the latter, substantially as set forth.
3. In an apparatus for the purpose described the combination of a casing having a coin passage or path, a pivoted depending swinging gate projecting into said path and a series of independent fingers pivotally supported on said gate below the pivot of the gate and having their ends arranged contiguous to the coin-path and adapted to impinge the coin therein, substantially as set forth.
4. In an apparatus for the purpose described the combination of a casing having a coin passage or path, a depending swinging pivoted gate projecting into said path, a fixed pivot from which said gate depends and a coin-interceptor comprising a finger pivoted to the lower swinging end of said gate and having its end arranged contiguous to said path, substantially as set forth.
5. In an apparatus for the purpose described, the combination of a casing having a coin passage, or path, a depending swinging gate pivoted at its upper end contiguous to said path, a projection, or incline, carried by said gate, and rigid therewith, and projecting into the path of the coin, and a series of coin-intercepting fingers pivoted at their lower ends to the lower end of the gate, and movable independently of the gate at their upper ends.
6. In an apparatus for the purpose described, the combination of a casing having a coin pas-

sage, or path, a gate arranged contiguous to said path, a fixed pivot supporting the upper end of said gate, the lower end of the gate being free to swing toward and from the coin-path, a projection from the gate extending into the coin-path and adapted to be impinged by the coin for throwing the lower end of the gate away from the coin-path, and a series of coin-intercepting fingers pivoted at their lower ends to the lower free end of the gate and fulcrumed at their upper ends against the upper part of the gate with their upper ends arranged contiguous to the coin-path and movable away from the coin-path independently of the gate.

7. In an apparatus for the purpose described, the combination of a casing having a coin passage, or path, a pivoted depending gate arranged contiguous to said path and movable at its lower end toward and from said path, a downwardly-extending incline formed on the face of the gate contiguous to the path of the coin and converging downwardly toward said path, and coin-intercepting fingers pivoted at their lower ends to said gate and having their upper ends arranged contiguous to the coin-path.

8. In an apparatus for the purpose described, the combination of a casing having a coin passage or path, a pivoted depending gate projecting into said path so as to be deflected by the coin and a coin-intercepting finger pivoted at its lower end to the lower end of the gate and supported at its upper end against the gate, whereby the outward movement of the lower end of the gate will cause the inward movement of the upper end of said finger.

9. In an apparatus for the purpose described, the combination of a casing having a coin passage or path, a swinging gate intercepting said path so as to be deflected by the coin, a coin-intercepting finger pivoted at its lower end to the lower swinging end of the gate, and means for fulcruming said finger near its upper end, whereby the outward swinging of the gate will cause the upper end of the finger to move toward the coin-path.

MARION N. TOMBLIN.
